UNITED STATES PATENT OFFICE

159,122

TEXTILE FABRIC

Sol Weinberg, New York, N. Y.

Application February 10, 1950, Serial No. 7,869

Term of patent 7 years

(Cl. D92—1)

To all whom it may concern:

Be it known that I, Sol Weinberg, a citizen of the United States of America, residing in New York city, county of New York, and State of New York, have invented a new, original, and ornamental Design for a Textile Fabric, of which the following is a specification, reference being had to the accompanying drawing, forming part thereof, wherein,

The figure is a plan view of a textile fabric showing my new design.

I claim:

The ornamental design for a textile fabric, substantially as shown.

SOL WEINBERG.
